UNITED STATES PATENT OFFICE.

RUDOLF HAAS, OF BADEN-BADEN, GERMANY.

MANUFACTURE OF HOLLOW BODIES FROM FIBROUS PULP.

Application filed November 12, 1925, Serial No. 68,691, and in Germany November 24, 1924.

It has already been proposed to manufacture hollow bodies from fibrous pulp by letting the quantity of fibrous pulp required each time flow into a mould having previous 5 walls and thereupon effecting the removal of water and the drying by means of a heated gaseous pressure medium.

The present invention constitutes a further improvement of such methods and consists more particularly in this, that the preliminary container which is interpolated between the supply pipe for the fibrous pulp and the mould is shut off from the mould while being filled, that the contents, after 15 the means for shutting off the said pipe have been opened again, are transferred to the mould and that the heated gaseous pressure medium is allowed to enter between the preliminary container and the mould in such a manner as to circumvent the preliminary container.

In the accompanying drawing three constructional examples of the invention are shown diagrammatically.

Figure I is a vertical section of the apparatus used.

Figure II is a modification also in vertical section showing the mold in position.

Figure III is a further modification of 30 a part of the device.

The fibrous pulp enters through the valve *a* from the supply pipe into the preliminary container *b*¹, *b*². When the latter has been sufficiently filled, the valve *c* which has so far cut off the mould *d* from the preliminary container is opened. By this means the fibrous pulp is passed into the mould *d*. When this has taken place, the valve *c* is closed and the gaseous heating medium is allowed to flow in through the valve *e*. While it is drying the hollow body to be moulded in the mould *d*, a fresh filling can flow through the valve *a* into the preliminary container *b*¹, *b*².

In the example shown in Figure 2 the preliminary container *b*² is of variable size, for instance by a piston *f* being so arranged as to be capable of being withdrawn to a greater or less extent by means of the spindle *g* and the hand-wheel *h*. By this means the weight of the body to be moulded can be accurately gauged.

Through the valve *i*, *i*² any suitable gaseous pressure medium may be introduced 55 for the purpose of accelerating the passage of the fibrous pulp from the preliminary

container *b*¹, *b*² into the mould *d*. Instead of this the piston *f* may for instance itself be used for forcing the pulp into the mould, in which case the preliminary container will 60 take the place of the delivering member. A similar effect may be obtained by the preliminary container being replaced by any suitable pulp pump of a known form (Fig. 3.).

It will be obvious, that at the end of each displacement of the fibrous pulp out of the preliminary container a certain quantity of liquid will remain in the mould itself or in the pipe leading to the mould, which quantity of liquid must first be forced out of the mould by the gaseous heating medium entering at *e* before the actual drying operation commences. For accelerating the operation in this case as well a 70 separate gaseous pressure medium may be introduced for instance through the valve *i*², before the heating medium is admitted at *e*. Alternatively, the arrangement according to the present invention may be such that 80 the residual liquid referred to above is removed from the mould to a greater or less extent through a pipe *k* which extends into the mould *d* and is controlled by a valve *l*, for which purpose the pressure of the gaseous heating or pressure medium entering at *e* or *i*² may be utilized. The emerging residual liquid may be introduced again at any suitable point in the path of the fibrous pulp, whereby it is caused to travel in a closed 85 circuit without any loss of pulp.

The new method has the following advantages:

1. An accurate measurement of the fibrous pulp and consequently great uniformity of 95 the products.
2. The avoidance of heat losses through the employment of the preliminary container.
3. A more uniform drying through the displacement of the residual liquid without 100 sacrificing the advantages provided by a mould which is filled from above.

What I claim is:

1. A method of manufacturing hollow bodies from fibrous pulp in moulds with previous walls by the use of a gaseous pressure medium, consisting in this that the fibrous pulp is first passed into a preliminary container whilst the same is shut off from the mould, whereupon communication is established between the container and the mould, whereby water is removed from the pulp in 110

the mould, and a gaseous heating medium is then admitted into the mould without passing through the preliminary container, as and for the purpose set forth.

5 2. A method as claimed in claim 1, and consisting in this that while the mass of fibrous pulp contained in the mould is being dried by the gaseous heating medium the fresh supply of pulp is admitted into the 10 preliminary container for the next moulding operation, as set forth.

15 3. A method as claimed in claim 1, and consisting in this that after the fibrous pulp has been conveyed from the preliminary container into the mould the liquid remaining in the mould itself and in the supply pipe for the same is forced out of the mould by a separate gaseous pressure medium.

20 4. A method as claimed in claim 1, and in which the removal of the water is accelerated by a greater or less portion thereof being forced out upwardly through a pipe extending into the mould under the action of the medium admitted to the mould, as set forth.

25 5. An apparatus for manufacturing hollow bodies from fibrous pulp, comprising in combination a container, a supply pipe for supplying pulp to the container, a pervious mould, a connecting pipe between the con-

tainer and the mould, a valve in the said supply pipe, a valve in the said connecting pipe, means for removing the residual liquid from the mould and means for admitting a gaseous heating medium directly into the mould, as and for the purpose set forth.

30 6. An apparatus as claimed in claim 5, and comprising means for forcing the fibrous pulp from the container to the mould, as set forth.

35 7. An apparatus for manufacturing hollow bodies from fibrous pulp, comprising in combination a container of variable capacity, a supply pipe for supplying pulp to the container, a pervious mould, a connecting pipe between the container and the mould, a valve in the said supply pipe, a valve in the said connecting pipe, means for removing the residual liquid from the mould and means for admitting a gaseous heating medium directly into the mould, as and for the purpose set forth.

40 8. An apparatus as claimed in claim 5 and comprising means for admitting a gaseous pressure medium into the container, as set forth.

45 55 In testimony whereof I have signed my name to this specification:

DR. ING. RUDOLF HAAS.
